Application April 13, 1944, Serial No. 530,762

11 Claims.

(Cl. 66—71)

The present invention relates to an improvement in knitting machines. Objects of said invention have been among others to provide improved stitch length change mechanism adapted for knitting machines more particularly of the links-links or knit-purl type; to provide effective means for making stitch length changes simultaneously on a plurality of individually operated knitting sections of a multiple machine; and to provide means which permit exact duplication of any given set of stitch lengths in making other units of product and/or at other operating times.

One embodiment of my invention in a form adapted for use in an automatic multiple links knitting machine and as described in the following specification is illustrated in the appended drawings in which:

Figure 1 is a front elevation of a knitting machine embodying the improved stitch length change mechanism;

Figure 2, a view partly in plan and partly in horizontal section of parts at the right-hand end of the machine as viewed in Figure 1;

Figure 3, an enlarged transverse vertical section on the line 3—3 of Figure 2;

Figure 4, an enlarged fragmentary view on the line 4—4 of Figure 2 showing the control links associated with the automatic stitch length control mechanism;

Figure 5, an enlarged end elevation of part of the left end of the machine shown in Figure 1;

Figure 6, an enlarged plan view of parts of the left end portion of the machine shown in Figure 1 with some parts removed and some broken away;

Figure 7, an enlarged front elevation, with parts in longitudinal vertical section and other parts broken away, showing more clearly jacquard shaft actuating devices at the left end of the machine shown in Figure 1, jack positioning devices and stitch length setting devices;

Figure 8, a transverse vertical section on the line 8—8 of Figure 7; and

Figure 9, a horizontal section on the line 9—9 of Figure 8.

In the arrangement, as shown in the drawings, the stitch cams, as 34 and 35 are mounted to reciprocate endwise in front and rear stitch cam guides or housings 36 and 37 respectively, Figures 2 and 6; and for effecting stitch length change, said housings are controllably movable either singly or together toward and away from the knitting off or opposed edge portions of their respective needle beds. Devices for effecting this movement are conveniently arranged to cooper-

ate with control means whereby movement of said housings or either of them may take place from any one to any other of a plurality of different positions representing a corresponding number of different stitch lengths. Means are also provided which permit adjustment to produce stitches of many different lengths in either bed within practicable maximum limits.

The stitch cams, as 34 and 35, Figure 2, are operatively connected to rods 40 which are actuated by a reciprocating arm 43 mounted to slide longitudinally of the machine on a fixed support and guide bar 44. Arm 43 is reciprocated by a chain 53 connected to opposite portions of one end of said arm and driven from a driving sprocket 65 mounted on a spindle 66.

The front and rear stitch cam housings 36 and 37 respectively, as seen more clearly in Figures 2, 3 and 6, are mounted to be adjusted toward 20 and from the inner edges of their respective needle beds to vary the length of stitches by the extent of said movement. This result follows because it produces a like adjustment between said edges and the front and rear stitch cams 25 respectively which are mounted in said housings. The latter are biased toward the edges of their respective needle beds by tension springs 104, each having one end secured near one end of one of said housings and the other end secured to 30 an adjacent end of the other housing.

To facilitate the adjustment just described, said housings 36 and 37 are supported at their ends to slide obliquely, Figure 6, i. e. with a combined endwise and in-and-out displacement in relation to fixed guides, shown in the form of guide plates 105 having angularly disposed guide surfaces 106. Oblique edge faces of wedges 107 extending from the inner edges of housings 36 and 37 slidably engage said guide surfaces 106. It 40 will be clear from the foregoing that, if a suitable force is applied against adjacent ends of said housings to displace them longitudinally, they will also move outwardly against tension of said springs 104 which hold said wedges 107 against 45 the guide surfaces 106; and that in such more outward positions of said housings, the stitch forming displacement of the needles by stitch cams 34 and 35 will be greater.

To effect and releasably maintain the adjustment of the stitch cams in relation to their respective beds for the purpose above stated, each housing is provided with a buffer plate 108, Figure 6, having outer contact faces 109 which lie opposite the path of movement of exposed end 55 portions of a set of longitudinally adjustable pins

110, two such sets of four each being mounted in radially arranged recesses in a quadrant shaped head or carrier 111 fixed at the upper end of a shaft 112.

Inner end portions of said pins 110 are provided with micrometer threads to permit accurate endwise adjustment thereof in their respective recesses to vary the extent to which the outer ends of said pins project beyond the peripheral face of carrier 111. To facilitate this adjustment and insure accuracy thereof, said respective pins 110 are provided with correspondingly spaced or graduated markings 110a on their peripheral surfaces and are releasably secured by set screws 110b in any desired extended position. This arrangement permits a wide range of stitch length variation to meet various pattern requirements.

In the preferred form shown, Figure 6, the markings "1, 2, 3," etc., are arranged in a spiral sequence so that each is clearly visible and may therefore be brought into exact register with fiducial markings 110c carried by the bevelled curved peripheral surface of carrier 111. Where the markings 110a on each pin 110 define the same increments of adjustment as the markings on each other pin, stitch length conditions can be accurately controlled and reproduced to obtain uniform results in different lots of goods, other conditions being the same.

Assuming that the pins 110 of each set thereof have been adjusted with their outer ends extending the required distances beyond the periphery of carrier 111, the outer ends of any selected pair of said pins are moved into and out of operative relation to the several contact faces 109 by rotating shaft 112 which actuates carrier 111. If by this angular movement, a more extended pin engaging one of the faces 109 is replaced by a less extended pin, a corresponding retractive movement of one of said housings 36 and 37 is effected by springs 104. If the replacement is in the opposite sense, the outer end of a more extended pin, bears cam-like against one of said faces 109 and forces and holds one of the housings 36 and 37 farther from the other until a subsequent change is effected. Likewise, corresponding pins in each set may be adjusted to effect the same extent of change in the positions of both housings.

Automatic stitch length change

For effecting a predetermined rotation of shaft 112 automatically, said shaft is journaled in a bracket 113, Figures 5, 7, 8 and 9, and has fixed to its lower end a fork 114 having spaced arms, end portions of which, Figure 8, provide guide journals for a vertically slideable spindle 115, Figures 7 and 8. The lower end of said spindle 115 is supported to slide freely in an arcuate path on the top surface of a T shaped upright link 116, the bottom end of which is pivotally secured to a lever 117 at 118. Said lever 117 is fixed to and turns with a stitch length control shaft 119 actuated in any suitable manner, as by automatic control devices including control links 303 and 304, Figures 2 and 4, connected to rock said shaft 119 predetermined increments to and from a neutral or inoperative angular position. An arm 120, Figure 8, has one end journaled in the frame at 121 and the other end pivotally connected to an upper end portion of link 116 at 122. Thus, when lever 117 is actuated by shaft 119 to move link 116 vertically, the latter remains upright and in proper supporting relation to spindle 115.

Selective stitch length change control

As seen in Figures 8 and 9, a selector or stop carrier in the form of a plate 123 is mounted on spindle 115 to move up and down therewith. A mid portion of said plate rests on an annular shoulder 124 of spindle 115 where it is secured by a nut 125. An end portion (left Figure 9) of plate 123 is provided with a curved slot 128 which engages a vertical guide pin 127 supported on a bracket 126. Adjacent said slot, plate 123 has an upwardly extending stop lug presenting two relatively stepped vertically disposed stop faces 129. At the opposite end of said plate 123, a similar but downwardly extending stop lug presents relatively stepped vertically disposed stop faces 130. As seen in Figure 9, an inward extension at the left end of selector plate 123 provides a vertically arranged stop shoulder 131 presenting a vertical face in stepped and aligned relation to said faces 129; and a similar extension at the opposite end provides stop shoulder 132 presenting a vertically arranged face in stepped and aligned relation to said faces 130. Thus, stop shoulder 131 and stop lug faces 129 provide a series of three vertical stop faces at the slotted end of plate 123; and stop shoulder 132 and stop lug faces 130 provide a series of three vertical stop faces at the other end of said plate 123.

As seen in Figures 7, 8 and 9, actuating devices 30 for imparting endwise motion to the selector plate 123 in its several operative positions and thus to rock fork 114 and rotate shaft 112, include parts mounted in a housing supported on posts 133 and having spaced walls 134 and 135. Inner wall 134 is provided with spaced axially aligned slots 136 (dotted Figure 8); and outer wall 135 with a lower slot 137 at its right end, Figure 8, and an upper slot 138 at its left end. In a lower portion of the space between walls 134 and 135 is a lower slide plate 139 provided with inwardly extending bosses 140 on which are mounted cam rollers 141 engaging the periphery of a cam 142 fixed on shaft 9. Slide plate 139 also carries on a portion of its upper edge a pusher arm 143 which extends horizontally through lower end slot 137 and into position to engage one or another of the stop faces 129, 132 on selector plate 123 depending on the position of said plate. Another portion of the upper edge of slide plate 139 is provided with an upwardly disposed rack 144, Figure 8.

A pinion 145 journaled on a shaft 146 engages said rack 144 and also a downwardly disposed rack 147 on the lower edge of an upper slide plate 148. A pusher arm 149 extending horizontally from said lower edge of upper plate 148 has a portion projecting through said upper end slot 138 in wall 135. Said arm is thus supported and guided in said upper slot 138; and its free end portion is positioned to engage one or another of the stop faces 129, 131 of the stops at the left, Figure 9, on selector plate 123 depending on the position of said selector plate.

In operation of the stitch length change devices above described, cam 142 revolves with rotation of shaft 9 to impart periodic to and fro motion simultaneously in opposite directions to said lower slide plate 139 and said upper slide plate 148, respectively, and consequently to the pusher arms 143 and 149 carried thereby. With cam 142 in the position shown in Figures 8 and 9, the slide plates 139 and 148 are in their extreme end positions, i. e. with pusher arm 149 on slide plate 139 spaced at the maximum distance from pusher arm 143 on slide plate 148. When shaft 9 is rotated to bring cam 142 180° from the illustrated position, pusher

arm 143 is spaced the minimum distance from pusher arm 149.

To effect a predetermined angular setting of the pin carrying head or quadrant 111, selector plate 123 is adjusted vertically by any suitable means to bring the corresponding one of its stop faces into position in the line of outward horizontal movement of one of the pusher arms 143 or 149.

In automatic operation suitable control mechanism causes upright link 116 to be moved downwardly from the normal or inoperative position shown in Figure 8 to a selected one of different predetermined operative positions by rotation of control shaft 119. This brings a predetermined stop face on said selector plate 123 into the path of horizontal movement of one of said pusher arms 143 and 149. Said plate is thereupon moved endwise in the direction of movement of the engaged pusher arm.

As shown in Figures 6, 8 and 9, at the last preceding stitch length setting, the selector plate 123 was moved to its extreme left end position, Figure 9, which brought carrier 111 into the end position shown in Figure 6. This setting resulted when selector plate 123 was operatively positioned at the next lower step from the normal inoperative position shown in Figure 8, and so that pusher arm 149, on its periodic outward-movement toward the left, engaged stop face 131, Figure 9. Thereafter, control shaft 119 was rotated back to its initial inoperative position, thus restoring selector plate 123 to its inoperative level or position but leaving the carrier in position as adjusted.

If the pattern should now require a stitch length produced, for example, by the effective setting of the pair of pins 110 next respectively to the pair shown in operating position in Figure 6, said last mentioned pair will be displaced and said next pair will be brought into operative position by a suitable clockwise (Figure 6) movement of carrier 111. For this purpose, the control devices bring selector plate 123 to a position two steps below that shown in Figure 8 and such that the end of pusher arm 143, in its next move to the right, will engage the lower stop face 130 to move selector plate 123 toward the right, Figure 8. Obviously, the extent of movement of said plate to the right depends on which of the stop faces 130, 132 is brought into position to be engaged by pusher arm 143. To move selector plate 123 in the opposite direction (left) to different positions, the pusher arm 149 in moving to the left will selectively engage the stop faces 129, 131 by proper controlled vertical positioning of said selector plate.

The stitch length change mechanism above described is of relatively simple construction and well adapted to control the position of a plurality of stitch cams operating simultaneously as a group over different portions of a single needle bed or in parallel groups over opposed beds. It is noted that the cam housings remain at each position of adjustment until a different stitch length is required; and changes may be made to take effect in a course beginning at either end of the needle bed.

The above described mechanisms are also shown and described but not independently claimed in my co-pending application Serial No. 530,761 filed herewith and of which the present application is in effect a division.

I claim:

1. In a knitting machine having a needle bed, 75

a stitch cam housing and a stitch cam mounted to slide longitudinally therein, said cam housing being supported to slide in relation to said needle bed, the combination of spring means for biasing said housing toward one edge of said needle bed, and means for imparting combined longitudinal and transverse movement to said housing against the resistance of said biasing means to change the position of said stitch cam in relation to said edge of the needle bed and thereby to change the length of stitch formed by operation of said stitch cam in knitting.

2. In a knitting machine having a needle bed, a stitch cam housing and a stitch cam mounted to slide longitudinally therein, said cam housing being supported to slide in relation to said needle bed, the combination of housing actuating means for imparting combined longitudinal and transverse movement to said housing to change the position of said stitch cam in relation to said edge of the needle bed, and adjustable means for varying the extent to which the position of the stitch cam is changed by operation of said housing actuating means.

3. In a knitting machine having a needle bed, a stitch cam housing and a stitch cam mounted to slide longitudinally therein, said cam housing being supported to slide in relation to said needle bed, the combination of housing actuating means for imparting combined longitudinal and transverse movement to said housing to change the position of said stitch cam in relation to said edge of the needle bed, and adjustable means for varying the extent to which the position of the stitch cam is changed by operation of said housing actuating means.

30 35 40 45 50 55 60 65

4. In a knitting machine having a needle bed, a slidably mounted stitch cam housing, a stitch cam carried thereby, a stop member having an obliquely disposed guiding surface, and a spring arranged and adapted to bias said housing toward an edge of said needle bed and against said guiding surface, the combination of a rotatable head, means for rotating said head from and to different angular positions in relation to said housing, and a plurality of spacing members mounted on said head and arranged and adapted to effect sliding movement of said housing from one position to another and to retain said housing in such new position.

5. In a knitting machine having a needle bed, a slidably mounted stitch cam housing, a stitch cam carried thereby, a stop member having an obliquely disposed guiding surface, and a spring arranged and adapted to bias said housing toward an edge of said needle bed and against said guiding surface, the combination of a rotatable head, means for rotating said head from and to different angular positions in relation to said housing, and a plurality of longitudinally adjustable spacing members mounted in radial relation on said head and arranged and adapted to severally engage and variously position said housing.

6. In a knitting machine having a needle bed, a slidably mounted stitch cam housing, a stitch cam carried thereby, a stop member having an obliquely disposed guiding surface, and a spring arranged and adapted to bias said housing toward an edge of said needle bed and against said guiding surface, the combination of a rotatable head, means for rotating said head from and to different angular positions in relation to said housing, and a plurality of longitudinally adjustable spacing members mounted in radial relation on said head and arranged and adapted to severally engage and variously position said housing.

ing members mounted in radial relation on said head and arranged and adapted to severally engage and variously position said housing, each of said members being threaded in said head and having spaced markings movable with said member toward and from an edge portion of said head when said member is rotated on its threads, and each marking representing a predetermined stitch length setting of said member when occupying a predetermined position of adjustment in relation to said edge portion of the housing.

7. In a knitting machine having a stitch cam housing slidably adjustable to change the length of stitches formed in operating a stitch cam carried thereby and a rotatable head arranged and adapted to move said housing and retain the same in different positions of adjustment for different stitch lengths, the combination of a selector member operatively connected to rotate said head different predetermined extents in opposite directions, said selector having opposed sets of stop faces arranged in stepped relation, a reciprocatable pusher for engaging each set of stop faces, means for imparting periodic reciprocating motion to said pushers simultaneously in opposite directions, and means for moving the selector member to bring a stop face of one of said sets into the path of movement of one of said pushers whereby said selector is moved in a direction to rotate said head.

8. Stitch length change mechanism for knitting machines including a rotatable head, a stop carrier operatively connected thereto and having stop portions arranged in stepped relation thereon, a carrier actuating device arranged and adapted to engage said stop portions, means for imparting periodic movement to said carrier actuating device toward and from said stop portions, and means for moving said carrier to and from different positions in relation to said carrier actuating device to bring one or another of said stop portions thereon into position to be engaged by said carrier actuating device.

9. Stitch length change mechanism for knitting machines including a rotatable head, a stop carrier operatively connected thereto and having stop portions arranged in stepped relation thereon, a carrier actuating arm arranged and adapted to engage said stop portions, means for reciprocating said arm toward and from said stop portions, a vertically adjustable link, a spindle operatively connected to said stop carrier and arranged with an end portion bearing on a portion of said link, and means for moving said link vertically to bring one or another of said stop portions on the carrier into position to be engaged by said carrier actuating arm.

10. Stitch length change mechanism for knitting machines including a link, means for adjusting said link endwise, a spindle arranged and adapted to slidably bear on a portion thereof, and movable with said link, a stop carrier mounted on said spindle and having at its opposite ends stop members extending therefrom in opposite directions, a pair of carrier actuating members each arranged and adapted to reciprocate toward and from the stops at one end of said carrier, and means for actuating said arms to engage one or another of said stops and thus to move said carrier.

11. In a knitting machine, the combination of a needle bed having needle grooves opening at one edge thereof and needles mounted in said grooves and movable through said openings, a stitch cam guide extending across said needle bed and arranged and adapted for adjusting movement toward and from said edge of the needle bed, a plurality of stitch cams slidably supported on said guide, means for effecting adjusting movement of said stitch cam guide, means for varying the extent of said adjusting movement, and means for reciprocating said stitch cams in relation to said guide and in a direction across said grooves at any position of adjustment of said guide in relation to said edge of the needle bed.

THOMAS S. HAYHURST.
